UNITED STATES PATENT OFFICE.

MATTHEW T. CHAPMAN, OF AURORA, ILLINOIS, ASSIGNOR TO THE AMERICAN WELL WORKS, OF AURORA, ILLINOIS, A CORPORATION OF ILLINOIS.

PUMPING MACHINERY.

1,157,676.

Specification of Letters Patent. Patented Oct. 26, 1915.

Application filed September 18, 1911. Serial No. 649,843.

To all whom it may concern:

Be it known that I, MATTHEW T. CHAPMAN, a citizen of the United States, residing at Aurora, in the county of Kane and State of Illinois, have invented certain new and useful Improvements in Pumping Machinery, of which the following is a specification, reference being had to the accompanying drawings.

10 This invention relates to pumping machinery and is particularly designed for use in connection with a deep well pump.

15 My improved pump comprises two plungers located in the well one above the other, adapted to lift the water alternately, the operating rod for one of said plungers being hollow so that the other operating rod may work inside of the first.

20 It is one of the objects of my invention to provide a new and improved means for causing the upward stroke of each plunger to occupy a greater proportion of the time than does the downward stroke. In this way, for an interval just after one of the 25 plungers has reached its lowermost point, both plungers are moving upward. Thus one plunger begins to move upward with the stream of water before the end of the upward stroke of the other plunger, with the 30 result that the water is forced upward in a continuous stream without being permitted to come to rest. This obviates the necessity for giving the stream of water a fresh start at the beginning of the stroke of each plunger, and thus materially lessens the strain 35 upon the pumping machinery.

Another object of my invention is to provide a new and improved arrangement of parts by which the power is applied directly 40 in line with the plunger-rods so as to avoid any side draft which would cramp the mechanism and make necessary the use of an undue amount of energy for raising a given quantity of water.

45 Another object of my invention is the provision of means for relieving all possible strain from the plunger-rods in the well by means of force pumps located at or near the surface by which the water may be delivered to the elevation required after being brought to the surface without requiring this work to be done by the lifting plungers.

It is another object of my invention to provide suitable mechanism and such an 50 arrangement of parts that, without changing

the position of the pump on its foundation, the driving crank shaft may be utilized to advantage for hoisting the plunger-rods out of the well for repairs.

Another object is the improvement of 60 pumping machinery in sundry details hereinafter pointed out.

The means by which I have accomplished these objects are illustrated in the drawings and hereinafter specifically described. 65

That which I believe to be new is set forth in the claims.

In the drawings:—Figure 1 is a side view of my improved machine; Fig. 2 is a top or plan view of the same; Fig. 3 is a front 70 view of my device; Fig. 4 is a rear view thereof; Fig. 5 is an enlarged detail, being a cross-section taken on line 5—5 of Fig. 1; Fig. 6 is an enlarged detail, being a section taken on line 6—6 of Fig. 2; Fig. 7 is an 75 enlarged detail of my improved crank; and Fig. 8 is an enlarged detail being a top view, partly broken away, of the parts shown in Fig. 7.

Referring to the several figures of the 80 drawings in which corresponding parts are indicated by the same reference characters—20 indicates the base located upon a foundation 21 built about the upper end 22 of the well tube. 85

23—24 indicates standards, mounted in the upper ends of which is a crank 25, said crank comprising cylindrical parts 26—27 revoluble in bearings 28—29.

30 indicates a gear bolted or otherwise 90 suitably secured to a central cylindrical part 31 of said crank.

32 indicates a shaft journaled in said frame in rear of said crank 25, mounted upon which is a gear 33 meshing with said 95 gear 30.

34 indicates a driving pulley mounted on said shaft 32, the outer end of said shaft being supported by any suitable bearing not shown. 100

35—36 indicate uprights bolted or otherwise rigidly secured to the base 20.

37 indicates a rod passing through said uprights 35—36 and mounted at its ends in said standards 23—24. 105

38 indicates washers or other suitable spacing blocks mounted on said rod 37, by which the uprights 36—37 are held firmly in position.

39—40 indicate levers pivotally connected 110

at their rear ends to the upper ends of said uprights 35—36, each of said levers, as best shown in Figs. 1 and 6, comprising two bars 41—42 spaced a distance apart by suitable blocks 43—44. 45—46 indicate slide-blocks each adapted to slide between the bars 41—42 of one of the levers 39—40. Each slide-block 45—46 embraces one of the wrist-connections 47—48 of the crank 25. It will thus be seen that whenever the driving wheel 34 is rotated by the application of suitable power the levers 39—40 are caused to rise and fall alternately.

49—50 indicate arms or links, pivotally mounted at their lower ends upon the base 20, to the upper ends of which are pivotally secured two levers 51—52. As best shown in Fig. 2, these levers 51—52 converge laterally toward their forward ends where they are connected, as hereinafter described, to the operating-rods leading to the plungers.

53 indicates a link pivotally connected at its lower end to the lever 51 and pivotally connected at its upper end to the forward end of the lever 39.

54 indicates a link pivotally connected at its upper end to the lever 52 and pivotally connected at its lower end to the forward end of the lever 40.

55—56 indicate guide-rods mounted at the forward end of the machine in bosses 57 mounted on plates 57 suitably secured to the base 20.

58 indicates bars extending forward from the upper ends of the standards 23—24, embracing at their forward ends the guide-rods 55—56.

59 indicates diagonal brace-rods extending from the upper ends of the standards 23—24 to the upper ends of the guide-rods 55—56.

60 indicates a cross bar connecting the upper ends of the guide-rods 55—56.

61—62 indicate cross-heads slidably mounted upon the guide-rods 55—56, the cross-head 61 being pivotally connected to the forward end of the lever 52, and the cross-head 62 being pivotally connected to the forward end of the lever 51. As best shown in Fig. 3, the cross-head 62 is connected at its middle point to the hollow plunger-rod 63 of the pump, and the cross-head 61 is connected at its middle point to the plunger-rod 64 which is located inside of and adapted to slide freely within the hollow plunger-rod 63.

65 indicates a guide and packing-head in the upper end of the well-tube 22 for the plunger-rod 63, provided with the usual follower 65^a for holding packing properly in position.

The operation of my improved machine is as follows:—With the drive wheel 34 driven by any suitable power, in the direction indicated by the arrow thereon in Fig. 1, the gear 30 and crank 25 will be driven in the

direction indicated by the arrow on said gear. When the wrist-connection 47, in the rotation of the crank, reaches the position indicated by the dotted line O—A, the crank will be at right angles to the lever 39 and the lever will have reached its highest point. When, thereafter, the wrist 47 reaches the position indicated by the line O—B said crank will again be at right angles to the lever and the lever will be in its lowermost position. Thus in the rotation of the crank 25 the lever 39 is being raised while the crank is moving from the line O—B to the line O—A, and said crank is descending during the shorter period of time while the crank is moving from the line O—A to the line O—B. In the construction shown the angle A—O—B equals approximately 140°.

In like manner it will be noted that the lever 40, actuated by the wrist-connection 48, also reaches its lowermost point when the crank stands in the position indicated by O—B and in its highest position when the crank reaches the position indicated by the line O—A. Thus each of the levers 39 and 40 is being raised during 11/18 of the time, and has a quick return on the inoperative stroke during the remaining 7/18 of the time. It will thus be seen that for each complete rotation of the crank there are two periods, each comprising 2/18 of the time of the complete rotation, during which both of the levers 39 and 40 are being raised.

As shown diagrammatically in Fig. 1, when the lever 39 is moved downward to the position indicated by the dotted line P—C, the lever 51 is, through the medium of the link 53, also moved downward to the position indicated by the line R—D, the cross-head 62 causing the forward end of the lever 51 to move in a vertical line, this being made possible by the pivoting of the link 49, such lever being pulled forward to the position indicated by the line R—E. Likewise when the lever 39 reaches the position P—F the lever 51 will have reached the position R—G with the lever 49 again in substantially the position R—E. In the same way when the lever 40 is raised and lowered the lever 52 is given a slight movement longitudinally of itself to permit the forward end of the lever 52 to move always in a vertical line upon the guides 55—56.

As best shown in Fig. 5, the crank 25 is provided at its ends, outside of the frames 23—24, with wrists 66—67, upon which are mounted the upper ends of piston rods 68—69 provided at their lower ends with pistons 70—71 which work in cylinders 72—73 for forcing the water to any desired point after it has been raised to the surface of the ground.

74 indicates a hoisting drum connected to the crank 25, through the medium of the wrist 66, in concentric relation thereto.

- This drum is provided for use in lowering the plunger-rods into or raising them out of the well, being used in practice in connection with any suitable derrick not shown, 5 this being possible by reason of the levers 51—52 and the cross-heads 61—62 being mounted so that they may be readily moved out of the way when disconnected from the plunger-rods.
- 10 By my construction I have provided a crank which takes up a minimum amount of space by reason of having two of the crank-arms made in circular form so as to be utilized as bearings by which the crank is journaled in the frame, and by having the third crank-arm made in circular form so as to be utilized as the hub for the driving gear. This makes a very strong, compact, shaft, with the bearings close to the crank portions and with the crank as a whole, therefore, well balanced.
- 15 By arranging my levers 51—52 diagonally of the frame and having them converge laterally into vertical alinement at their front 20 ends and by having their forward ends slide upon the vertical guides 55—56, I provide a very efficient power-transforming mechanism which is especially valuable in a pump of this type.
- 25 The levers 51—52 have been described as having movement longitudinally of themselves, and by this I mean the longitudinal movement of the lever such as is attained by the swinging of the lever in such a way as to 30 keep its free end constantly in a direct vertical path, as distinguished from the longitudinal movement of the lever swinging upon a fixed pivot. The claims are therefore to be construed accordingly.
- 35 What I claim as my invention and desire to secure by Letters Patent, is,—
- 40 1. In a pump, the combination of a gear, means for driving said gear, two levers adapted to swing up and down beside said gear, means connecting said levers with said gear whereby upon the rotation of the gear said levers are reciprocated in opposite directions, two other levers adapted to swing up and down, connections between each of 45 said first-named levers and one of said second-named levers for causing them to swing in unison, two plunger-rods, and connections between said plunger-rods and said second-named levers respectively.
- 50 2. In a pump, the combination of a gear, means for driving said gear, two levers adapted to swing up and down beside said gear, means connecting said levers with said gear whereby upon the rotation of the gear said levers are reciprocated in opposite directions, two arms adapted to swing back and forth, two other levers pivotally mounted on said arms and adapted to swing up and down and to move forward and back 55 with said arms, connections between each of
- 55 said first-named levers and one of said second-named levers for causing them to swing in unison, two plunger-rods, connections between said plunger-rods and the forward ends of said second-named levers, and means 60 for maintaining the forward ends of said second-named levers in vertical alinement with the plunger-rods.
- 65 3. In a pump, the combination of a gear, wrists extending from the opposite faces of said gear on opposite sides of the axis of rotation of the gear, two levers adapted to swing up and down beside said gear, each of said levers being provided with a slide-box in which the wrist at that side of the gear 70 works, two arms adapted to swing back and forth, two other levers pivotally mounted on said arms and adapted to swing up and down and to move forward and back with said arms, two vertically-extending links 75 each of which pivotally connects one of said first-named levers with one of said second-named levers for causing said two connected levers to swing in unison, two plunger-rods, connections between said plunger-rods and the forward ends of said second-named levers respectively, and means for maintaining the forward end of each of said second-named levers in vertical alinement with the 80 respective plunger-rod.
- 85 4. In a pump, the combination of a gear, a wrist extending from each face thereof, two links adapted to swing back and forth, two levers mounted on said links and converging laterally toward their forward ends 90 into vertical alinement, two plunger-rods, connections between said levers and said plunger-rods, respectively, and connections between said levers and said wrists, respectively, whereby by the rotation of said gear 95 said levers and said plunger-rods are reciprocated in opposite directions.
- 100 5. In a pump, the combination of a gear, a wrist extending from each face thereof, two levers converging laterally toward their forward ends into vertical alinement, said levers being capable of a slight movement longitudinally of themselves, two plunger-rods, connections between said levers and said wrists whereby by the rotation of said 105 gear said levers are reciprocated, connections between said levers and said plunger-rods respectively and means for holding the forward ends of said levers directly in line with said plunger-rods.
- 110 6. In a pump, the combination of a gear, a wrist extending from each face thereof, two levers one on each side of said gear, each lever being provided with a slot in which the wrist on that side of the gear is adapted 115 to work, two plunger-rods, two levers converging laterally toward their forward ends into vertical alinement, said last-named levers being connected with said plunger-rods, and means operatively connecting said 120
- 125
- 130

last-named levers with said first-named levers.

7. In a pump, the combination of two plunger-rods, two levers converging laterally toward their forward ends into vertical alinement, said levers being capable of a slight movement longitudinally of themselves, said levers being connected with said plunger-rods, means for swinging said levers up and down, and means for holding the forward ends of said levers directly in line with said plunger-rods.

8. In a pump, the combination of two plunger-rods, two levers converging laterally toward their forward ends into vertical alinement, said levers being capable of a slight movement longitudinally of themselves, said levers being connected with said plunger-rods, means for swinging said levers up and down, and vertical guides for the forward ends of said levers whereby the same are reciprocated in a vertical line.

9. In a pump, the combination of two plunger-rods, two levers converging laterally toward their forward ends into vertical alinement, said levers being capable of a slight movement longitudinally of themselves, means for swinging said levers up and down, vertical guides, and cross-heads adapted to slide up and down thereon, each of said cross-heads having one of said levers and one of said plunger-rods connected thereto.

10. In a pump, the combination of two plunger-rods, two vertical links, two horizontal levers pivotally mounted on the upper ends of said vertical links and converging laterally toward their forward ends into vertical alinement, each of said horizontal levers being connected to one of said plunger-rods, means for swinging said levers up and down, and means for holding the forward ends of said levers directly in line with said plunger-rods.

11. In a pump, the combination of two levers, means for swinging said levers up and down, two plunger-rods, two other levers converging laterally toward their forward ends into vertical alinement, connections between said plunger-rods and said laterally-converging levers, and connections between said first-named levers and said laterally-converging levers whereby by the reciprocation of said first-named levers said plunger-rods are moved up and down.

12. In a pump, the combination of two levers, means for swinging said levers up and down, two plunger-rods, two other levers converging laterally toward their forward ends into vertical alinement, said levers being capable of a slight movement longitudinally of themselves, connections between said plunger-rods and said laterally-converging levers, connections between said first-named levers and said laterally-converging levers

whereby by the reciprocation of said first-named levers said plunger-rods are moved up and down, and means for holding the forward ends of said laterally-converging levers directly in line with said plunger-rods.

13. In a pump, the combination of a frame, two plunger-rods, two levers converging laterally toward their forward ends into vertical alinement, said levers being capable of a slight movement longitudinally of themselves, each of said levers being connected with one of said plunger-rods, means for holding the forward ends of said levers directly in line with said plunger-rods, two other levers pivoted on said frame, a crank by the rotation of which said last-named levers are reciprocated up and down, and links connecting the free ends of said last-named levers with said first-named levers.

14. In a pump, the combination of two levers, means for swinging said levers up and down, two plunger-rods, two vertical links adapted to swing back and forth, two other levers pivotally mounted upon the upper ends of said links and converging laterally toward their forward ends into vertical alinement, connections between said plunger-rods and said laterally-converging levers, connections between said first-named levers and said laterally-converging levers whereby by the reciprocation of said first-named levers said plunger-rods are moved up and down, and means for holding the forward ends of said laterally-converging levers directly in line with said plunger-rods.

15. In a pump, the combination of two levers, means for swinging said levers up and down, two plunger-rods, two vertical links adapted to swing back and forth, two other levers pivotally mounted on the upper ends of said links and converging laterally toward their forward ends into vertical alinement, connections between said plunger-rods and said laterally-converging levers, links pivotally connecting said first-named levers to said laterally-converging levers whereby by the reciprocation of said first-named levers said plunger-rods are moved up and down, and means for holding the forward ends of said laterally-converging levers directly in line with said plunger-rods.

16. In a pump, the combination of two levers, means for swinging said levers up and down, two plunger-rods, two other levers converging laterally toward their forward ends into vertical alinement, connections between said plunger-rods and said laterally converging levers, a link pivotally connecting one of said first-named levers to one of said laterally converging levers, and another link pivotally connecting the other of said first-named levers and the other of said laterally converging levers, whereby by the reciprocation of said first-named levers said plunger-rods are moved up and down.

17. In a pump, the combination of a gear, a wrist extending from each face thereof, two levers one on each side of said gear, each lever being provided with a slot in which the wrist on that side of the gear is adapted to work, two plunger-rods, two levers converging laterally toward their forward ends into vertical alinement, said last-named levers being connected with said 10 plunger-rods respectively, a link pivotally connecting one of said first-named levers with one of said laterally converging levers, and another link pivotally connecting the other of said first-named levers with the 15 other of said laterally converging levers.

18. In a pump, the combination of a gear, a wrist extending from each face thereof, two levers one on each side of said gear, each lever being provided with a slot in which the 20 wrist on that side of the gear is adapted to work, two plunger-rods, two swinging links, two levers mounted respectively on said links and converging laterally toward their forward ends into vertical alinement, connections 25 between said plunger-rods and said laterally converging levers respectively, a link pivotally connecting one of said first-named levers with one of said laterally converging levers, and another link pivotally 30 connecting the other of said first-named levers to the other of said laterally converging levers.

19. In a pump, the combination of a plunger-rod, a crank-shaft, means connecting 35 said plunger-rod and said crank-shaft whereby by the rotation of said shaft said plunger-rod is reciprocated up and down, and a hoisting-drum rotatable by means of

said crank-shaft, said means for connecting the plunger-rod and the crank-shaft being 40 capable of removal so that the hoisting-drum may be utilized for drawing the plunger-rod out of the well without moving the pump as a whole.

20. In a pump, in combination, a crank 45 shaft, two levers operated by said crank shaft, plunger-rods operatively connected with said levers and extending downwardly therefrom and adapted to raise water to the level of said pump,—said crank shaft comprising wrists at its ends,—and plunger-rods 50 operated by said wrists adapted to force said water to a higher level.

21. In a pump, in combination, a crank 55 shaft, two levers operated by said crank shaft, plunger-rods operatively connected with said levers and extending downwardly therefrom and adapted to raise water to the level of said pump,—said crank shaft comprising wrists at its ends formed integrally 60 therewith,—and plunger-rods operated by said wrists adapted to force said water to a higher level.

22. In a pump, in combination, a crank 65 shaft, plunger-rods adapted to be reciprocated thereby for raising water to the level of said pump, and other plunger-rods parallel with said first-named plunger-rods adapted to be reciprocated by said crank shaft for forcing said water to a higher 70 level.
